(No Model.)

J. WRIGHT.

HINGE.

No. 375,038.

Patented Dec. 20, 1887.

N. PETERS, Photo-Lithographer, Washington, D. C.

UNITED STATES PATENT OFFICE.

JACOB WRIGHT, OF MITCHELL, DAKOTA TERRITORY.

HINGE.

SPECIFICATION forming part of Letters Patent No. 375,038, dated December 20, 1887.

Application filed April 18, 1887. Serial No. 235,235. (No model.)

To all whom it may concern:

Be it known that I, JACOB WRIGHT, a citizen of the United States, residing at Mitchell, in the county of Davison and Territory of Dakota, have invented a new and useful Improvement 5 in Adjustable Hinges, of which the following is a specification.

My invention relates to an improvement in adjustable hinges; and it consists in the novel 10 construction and arrangement of the parts of the same, which will be more fully hereinafter described, and pointed out in the claims.

One object of my invention is to provide a hinge by which a door which may have become warped or shrunken may be adjusted in 15 its relative position to the jamb and with respect to the striker-plate by simple means, which are convenient and accessible, and which do not necessitate the removal of the 20 door to operate them.

A further object of my invention is to provide an adjustable hinge to be used in connection with doors, which is simple and effective in its construction and operation, strong and 25 durable, easily handled and readily understood, applied in connection with any door now in use, positive in its result, and cheaply manufactured.

I attain these objects by the mechanism illustrated in the accompanying drawings, wherein like letters of reference indicate similar parts in the several views, and in which—

Figure 1 is a perspective view of the door and a portion of the jamb, showing my improved hinge in connection therewith. Fig. 35 2 is a perspective view of my improved hinge, the parts thereof being shown separated. Fig. 3 is a top plan view of the parts of the hinge united. Fig. 4 is a perspective view of the 40 said hinge united, the one leaf thereof being removed. Fig. 5 is a sectional view on line xx of Fig. 4.

A indicates a leaf of a hinge of the ordinary form of construction, having a central knuckle, 45 a , and a recess, a' , in the face thereof. This leaf A is adapted to be screwed in connection with the rear edge of the door, as in the usual manner of hanging doors.

B represents the other leaf of the hinge, 50 which is constructed in the form of an angle-plate, having two plates, b and b' , united at

right angles, and at the intersection of which two knuckles, b^2 , are formed, between which the knuckle a of the leaf A engages and is retained by the pintle b^4 , passing through said 55 knuckles and into the lower retaining-lug, b^2 , as shown. The plate b' is also provided with a recessed face, b^6 , and has a screw, C, passing therethrough and retained in connection therewith by two plates, $c c$, encircling the rear portion of said screw on the opposite side of the plate b' . These plates $c c$ are securely fastened to the rear face of the plate b' and engage with a recess formed in the shank of the screw, and thereby retain the head thereof in a fixed position with respect to the outer surface of the plate b' . When the hinge entire is shut, by closing the door to which it is attached, the recesses a' in the leaf A and b^6 in the plate b' 60 form a combined recess which passes over the head of the said screw C without causing any projection thereby. The portion b of the plate B is shorter than the plate b' , and is provided with two slots, b^7 , which are elongated and operate as will be presently described. 65

In a suitable rabbet formed in the door-jamb W a plate, D, is secured, as more fully illustrated in Fig. 2 of the drawings. This plate B is of similar configuration to the plate B, which engages therewith, being an angle plate 80 provided with the two plates d and d' , intersecting each other at right angles. The face d' of the plate D is provided with the series of screw-holes d^2 , through which wood-screws pass and secure the same to the door-jamb W. 85 At about the central portion of the said plate d' a countersunk circular recess, d^3 , is constructed, in the central portion of which an aperture, d^4 , is bored, which extends through a boss, d^1 , formed integrally with the rear face 90 of the said plate d' . This boss is provided with a female screw-thread, and which is adapted to be engaged by the screw C, the recess d^3 fitting over the two retaining-plates $c c$ on the rear face of the plate d' of the section B of the hinge. The portion d of the plate D is provided with two screw-holes, d^5 , and has also right-angled projections d^6 at each end thereof. When the sections D and B of the hinge are 95 united, the plate d of the section D rides over the surface of the plate b of the section B between the angular projections d^6 , the slots d^7 100

in the portion d of the section B engaging and passing over the screw-holes d' in the section D. Suitable screws, E E, pass through the elongated openings b' and into the screw-holes d' , and are adapted to rigidly clamp the section B in connection with the section D.

It will be understood that the screws C and E will be machine-screws, and the operation of adjusting the hinge will be as follows: If, after the hinge is applied, the door to which it is connected should become displaced from its relative position with the jamb and striker-plate, and perchance sag downward, the screw C is turned in such a direction that the plate B will slide away from the plate D, it being understood that the screws E have previously been loosened. The screws E will then be tightened and clamp the section D in connection with the section B, and rigidly hold the hinge in its adjusted position. If, on the contrary, the door will bind at any point, the screw C is screwed home into the boss d'' and the section B of the hinge drawn toward and over the section D and the door drawn away from the opposite side of the jamb or the part with which it impinges, and the screws E E then caused to clamp the two parts together, as heretofore described. The section B of the hinge is inserted in the jamb of the door, with the boss thereof passing into an opening formed in the said jamb, which acts as an auxiliary for retaining the hinge in addition to the securing-screws thereof. The section B is unsecured at any point, except to the leaf A, as hereinbefore described, and is adjustably held in connection with the section D by means of the clamping-screw E E and the adjusting-screw C.

By this construction of hinge a convenient

and accessible means is provided for preventing the binding of doors in connection with 40 jambs, and when they do bind to easily adjust the same to obviate the annoyance caused thereby.

The novelty and utility of my improved hinge are apparent and its practicability obvious, and it is readily seen that slight variations in the construction and arrangement of the several parts can be made and substituted for those herein shown and described without in the least departing from the nature and principle of my invention.

Having described my invention, I claim—

1. In a hinge, the leaf A, the section B, constructed in the form of an angle-plate, having the portions b b' , the adjusting-screw C in the portion b' of the section B, the section D, with which the screw C engages, and the set-screws E in the portion b of the section B, as set forth.

2. The combination, with the leaf A, of the angular portion B, having the two plates b and b' , with the elongated apertures b' formed in the former and the screw C retained in connection with the latter, the section D, having the two plates d and d' , the guide projections d'' on the plate d , and the screws E E, working 65 through the apertures b' , substantially as described.

In testimony that I claim the foregoing as my own I have hereto affixed my signature in presence of witnesses.

JACOB WRIGHT.
